UNITED STATES PATENT OFFICE.

RICHARD DUANE GREEN, OF TRENTON, NEW JERSEY, ASSIGNOR TO JOHN A. ROEBLING'S SONS COMPANY, OF TRENTON, NEW JERSEY, A CORPORATION OF NEW JERSEY.

WIRE ROPE.

1,405,837.

Specification of Letters Patent. Patented Feb. 7, 1922.

Application filed January 8, 1920. Serial No. 350,151.

To all whom it may concern:

Be it known that I, RICHARD DUANE GREEN, a citizen of the United States, residing at Trenton, county of Mercer, and State 5 of New Jersey, have invented certain new and useful Improvements in Wire Ropes, fully described and represented in the following specification and the accompanying drawings, forming a part of the same.

10 Wire ropes for general hoisting purposes, where sheave work requires considerable flexibility, are generally formed with a fibre core of manila or other suitable fibre and the wire strands are laid up helically on 15 this core.

With particularly heavy duties such as encountered in present day commercial use, the excessive tension, by a concentration of pressure on the fibre strands, or the like, 20 eventually causes disintegration of the fibre core. When the fibre core thus ceases to function, the wire strands are supported only by each other, and the result is a tendency of the strand wires to nick. This nicking not only shortens the life of the rope, 25 but tends to lock the strands, thus restricting strand and wire movement when the rope is used in sheaves, causing the wires to break.

30 It is the especial object of the present invention to provide a heavy duty wire rope such that the fibre core is given a higher compressive resistance and nicking of the strand wires is prevented, and an extended bearing for the rope strands is provided, 35 thus making possible a wire rope of higher efficiency and longer life. The invention is applicable generally to wire rope, however, whether desired for light or heavy duty.

40 With this general object in view, the invention consists in the combination, details of construction and arrangements of parts which will first be described in connection with the accompanying drawing and then 45 more particularly pointed out in the claims.

In the drawing—

Figure 1 is a plan view, with parts broken away, of a wire rope embodying the invention; and

50 Figure 2 is a cross-sectional view taken through the completed rope.

Referring to the drawing, there is provided a fibre core 11 shown as formed of a number of strands laid up helically in the 55 usual manner of a fibre core. This core

may be constructed of manila, or any other suitable fibre.

To prevent a concentration of pressure on the strands of the core, the invention includes a tenacious protector for the core, 60 and in structures embodying the invention to the best advantage, this protector is laid up on the core to place the same under an initial compression. Although capable of various constructions, in the present embodiment, there is provided a tenacious protector in the form of a narrow, flat, steel band or flat wire 12. This band or flat wire is laid up helically on the fibre core under considerable tension, so that the core is 70 placed under an initial compression. The band or flat wire 12 is preferably so laid up that the edges of adjacent convolutions are substantially contiguous so as to fully enclose the core and hold the lubrication 75 therein. These edges are shown as square but they may be rounded if desired; and this may be preferable, especially in large ropes, as avoiding all possibility of the edges cutting the core. A half round or similar form 80 of band may be used, with the rounded side next the core, which will taper off the pressure on the core, and reduce the liability to injuring the core in bending over sheaves. For convenience in manufacture, the protecting band 12 may be of several alternating pieces, two being shown in the drawings. 85

Laid up about the protected core are a plurality of wire strands 13, each strand preferably consisting of a plurality of individual small wires. These wires are preferably of high carbon steel and are helically laid up on each other in the usual manner of making wire rope strands. Although six wire strands of nineteen wires 90 each are shown, it is understood that any other suitable arrangement may be used.

The protecting band 12, here illustrated, is preferably formed of high carbon steel that is hard enough to resist any substantial deformation under pressure of the wire strands. To provide a suitable extended bearing for the wire strands and to aid in preventing nicking of the high carbon steel wires of the strands, the invention includes 100 separating bearers for the wire strands substantially conforming to the shape thereof. In structures embodying the invention to the best advantage, these separating bearers are previously shaped to conform substan- 110

tially to the shape of the wire strands. Although capable of various constructions, in that shown, helically laid up on the protected core are a plurality of separating bearers 14, equal in number to the wire strands 13. These bearers are laid up on the core with the same pitch as the rope strands 13 and so as to lie between them. In the particular embodiment illustrated as 10 an example, the separating bearers separate the wire strands from one another as well as from the protected core. To this end, the bearer is shaped to the three sided, concave-faced form shown in the drawing, 15 which provides for each separating bearer a rib 15 which extends between two adjacent strands and separates them. On each side of the ribs 15 are wing portions 16 which separate the strands from the protected core.

The separating bearers 14 may be made of hard steel or of soft, annealed steel. In the latter case, there will be some deformation of the bearers under the tension exerted in laying up the wire strands, which deformation is increased when the completed rope is placed under high tension work. Such deformation causes the bearers to more fully conform to the configuration of the strands 20 and the shape of the bearing surfaces.

In either case, that is to say, with either hard or soft, deformable separating bearers, the result is an improved rope. With the construction described, the pressure of the 25 wire strands is taken by the protecting band 12 and the compressed core 11. This prevents direct pressure of the strands on the fibre core. The initial pressure given the fibre core in laying up the protecting band 30 flattens out, to a certain extent, the corrugations of the fibre strands, thus presenting a more cylindrical surface to the protector. The separating bearers 14 give an extended bearing to the wire strands and separate 35 them from one another and from the protected core.

As a result of the construction described, concentration of pressure on the fibre strands is prevented, the fibre core has a much higher 40 compressive resistance, and the life of the rope is prolonged. Further, nicking of the wires is prevented, the strands and wire move more freely, better lubrication is made possible, and the rope is more flexible and 45 has a higher efficiency, that is, a higher percentage of the total strength of the component wires, than the usual fibre center ropes.

While the invention has been described in 50 connection with the usual fibre or rope

strand cores, and is especially valuable in such use, it will be understood that the invention, considered broadly, is applicable also with other compressible cores, as defined by the claims.

What is claimed is:

1. A wire rope comprising a compressible core, a tenacious metal protector therefor, a plurality of wire strands laid up helically about the protected core, and separating bearers for the wire strands, substantially conforming to the shape thereof. 65

2. A wire rope comprising a compressible core, a tenacious protector laid up on the core to place the same under an initial compression, a plurality of wire strands laid up helically about the protected core, and separating bearers for the wire strands, substantially conforming to the shape thereof. 70

3. A wire rope comprising a compressible core, a tenacious protector therefor, a plurality of wire strands laid up helically about the protected core, separating bearers for the wire strands substantially conforming to the shape thereof and formed of metal 80 softer than the strand wires. 85

4. A wire rope comprising a compressible core, a hard, tenacious protector laid up on the core to place the same under an initial compression, a plurality of wire strands laid up helically about the protected core, separating bearers for the wire strands substantially conforming to the shape thereof and formed of metal softer than the strand wires. 90

5. A wire rope comprising a compressible core, a tenacious protector therefor, a plurality of wire strands laid up helically about the protected core, separating bearers for the wire strands shaped to have separating 95 ribs extending between the strands. 100

6. A wire rope comprising a compressible core, a tenacious protector therefor, a plurality of wire strands laid up helically about the protected core, and separating bearers for the wire strands shaped to have separating ribs extending between adjacent strands and wing portions on each side of said ribs for separating the strands from the 105 protected core. 110

7. A wire rope comprising a compressible core, a tenacious protector therefor, a plurality of wire strands laid up helically about the protected core, and separating bearers for the wire strands previously shaped to 115 substantially conform to the shape thereof.

In testimony whereof, I have hereunto set my hand.

RICHARD DUANE GREEN.
